UNITED STATES PATENT OFFICE.

GEORGE PALM, OF BUTLER, PENNSYLVANIA.

ATTACHMENT FOR STEAM-ENGINES.

SPECIFICATION forming part of Letters Patent No. 618,434, dated January 31, 1899.

Application filed December 18, 1897. Serial No. 662,403. (No model.)

To all whom it may concern:

Be it known that I, GEORGE PALM, a resident of Butler, in the county of Butler and State of Pennsylvania, have invented a new and useful Improvement in Attachments for Steam-Engines; and I do hereby declare the following to be a full, clear, and exact description thereof.

My invention relates to engines.

In the oil-fields there are great numbers of a certain type of steam-engines which are particularly adapted to the drilling of oil-wells. After a well has been drilled the same engine is often employed for operating the pump. There is considerable expense, however, attached to operating a steam-engine, especially when the wells are located at inaccessible points, as they often are, where it is difficult to obtain fuel and water. Gas-engine have been introduced to some extent for pumping purposes, but for drilling they have not been found to be practicable, owing to the severe treatment to which an engine is subjected in drilling. To employ a steam-engine for drilling and then incur the additional expense of purchasing a gas-engine for pumping purposes would greatly reduce the profits arising from a well, especially if the well is not one of large capacity. Furthermore, even after a gas-engine has been substituted for the steam-engine it may be necessary to drill the hole deeper, draw the casing, or do some other work in connection with the well for which the gas-engine is inadequate. Then the steam-engine must be employed. The result is that many wells have a gas-engine for pumping and keep in reserve the steam-engine, which may be brought into play when necessary.

The object of my invention is to provide an attachment for steam-engines whereby said engines may be quickly converted into a gas-engine, or vice versa.

My invention comprises the novel features hereinafter described and claimed.

To enable others skilled in the art to make and use my invention I will describe the same more fully, referring to the accompanying drawings, in which—

Figure 1 is a side view of a steam-engine with my invention applied thereto. Fig. 2 is an enlarged longitudinal section of the cyl-

inder with my invention attached thereto. Fig. 3 is an end view of the attachment. Fig. 4 is an interior end view of same. 55

Like letters indicate like parts in each of the figures.

The letter *a* designates the foundation upon which the steam-engine *A* rests. This engine is composed of the customary parts, 60 which do not need detailed description.

The cylinder *b* has the stuffing-box *c* at the forward end thereof, through which the piston-rod *d* passes and to which the piston *e* is attached. This piston *e* is illustrated as cup-shaped, although it may be of the ordinary construction. 65

The ports *f* *f'* are the ordinary steam-ports leading to the cylinder *b* and controlled by the oscillating valve *g*. The steam-inlet is 70 represented by the letter *h* and the exhaust by the letter *i*.

A water-jacket *k* surrounds the cylinder *b*, and if my invention is applied to a steam-engine not provided with such water-jacket it 75 is apparent that such a water-jacket may be readily constructed between the flanges at the front and rear heads of the cylinder, as indicated by dotted lines, Fig. 2. Pipes *l* *l'* are provided for admitting and carrying off 80 water.

Secured to the rear end of the cylinder *b* is the box or shell *M*. While this box or shell *M* is illustrated and described as cylindrical in form, yet I do not wish to limit myself to 85 any particular shape. Within said shell *M* is the inlet-chamber *m*, to which the explosive, such as gas and air, is admitted by the inlet *m'*. Ports *m*² lead from this chamber *m* to the chamber *n*, and said ports are controlled by the valve *n'*. This valve *n'* has a stem *n*², which passes up through a suitable guide and may extend into the cap *o* at the upper end of said shell. A spring *o'*, encircling the stem *n*², is interposed between the 95 nut on the end of said stem and the bottom of chamber *m*, so that the valve *n'* is normally closed. Below the chamber *n* is the exhaust-chamber *p*, which is controlled by a valve *p'*, whose stem *p*² passes down through 100 an opening in said exhaust-chamber and stuffing-box *q*. A spring *q'* is interposed between the stuffing-box *q* and the bifurcated end *q*² of said stem *p*², which acts to normally close

the valve p' . Jounaled in the bifurcated end q^2 of the stem p^2 is the roller r . This roller r is engaged by a cam r' on the shaft r^2 . On the shaft r^2 is the sprocket-wheel s , which is connected by the chain s' with the sprocket-wheel s^2 on the main shaft t , which carries the fly-wheel t' .

Secured to the shell M is the igniter U , which consists of the hot tube u , surrounded by the larger tube u' . A gas-pipe u^2 admits gas to the outer tube u' , while the openings u^3 supply the air. The ignition of the gas keeps the hot tube u at a high heat. The passage u^4 keeps the chamber n in communication with the hot tube and the gases are accordingly exploded, as will more fully hereinafter appear.

Secured to or forming part thereof, if desired, of the shell M is the disk v , said disk having the bolt-holes v' , through which the bolts pass which secure said disk to the flanges b' around the end of the cylinder b . This disk v has the opening v^2 , which brings the chamber n into communication with the cylinder b . A water-passage w is formed in the disk v , said water-passage communicating with the water-jacket k by means of the ports w' . The water enters by the pipe l and, passing through the disk, enters the water-jacket k , so that a constant circulation of the water is maintained.

The disk v has the inwardly-extending neck or collar x , which enters the cylinder b , fitting snugly therein. This neck x rests against a shoulder x' in said cylinder. A tight joint is thus obtained. This neck x also cuts off the steam-port f' . Any other suitable form of projection on the disk v which will cut off the steam-port f' may be employed.

Where a steam-engine has been in use for drilling purposes and is already on the ground, it may be readily converted into a gas-engine for use in pumping the well in the following manner: The rear cylinder-head is first removed, and the shell M is secured to the cylinder by inserting the neck x of the disk v into the cylinder and by bolting said disk to the flanges b' of said cylinder. The disk thus forms the rear end of cylinder, while the opening in the center thereof brings the cylinder into communication with the shell M . If the cylinder is not already provided with a water-jacket, one can be readily provided

by encircling the cylinder between its flanges at the end thereof with sheet-iron. When the shell M has thus been secured in place, the engine is then ready for operation. Steam may be employed to start the engine, as the port f is still open and steam can be admitted at one end of cylinder. To draw in the first charge of the explosive mixture, the fly-wheel may be turned by hand. The gas and air are admitted to the chamber n , and as the piston travels forward a vacuum is formed, which causes the valve n' to open and allow the explosive mixture to enter the chamber n , whence it may pass to the cylinder. As the piston returns the explosive mixture is compressed, the cup-piston acting to form such compression-chamber. When the gases have been compressed, they will then be exploded by the hot tube of the igniter, which is brought into direct contact with said gases. The explosion drives the piston forward. The cam r' , working on the roller r , acts to elevate the valve p' at the proper time to allow the exploded gases to escape into the exhaust-chamber p .

If for any reason more power is needed, the steam may be admitted to front end of cylinder, so that the piston will have steam on one end and gas on the other, or if for any reason still greater power is needed the engine may be quickly transformed into a complete steam-engine.

What I claim as my invention, and desire to secure by Letters Patent, is—

In an engine, the combination of a cylinder having steam-ports at each end thereof, a valve controlling said ports, a piston, a box or shell having a chamber therein with inlet and exhaust ports for the admission thereto and discharge therefrom of the live and dead gases, an igniter and a disk on said box or shell having a projection adapted to fit with in one end of the engine-cylinder and close the steam-port adjacent thereto, said disk having an opening therein whereby said chamber is in communication with said cylinder, substantially as set forth.

In testimony whereof I, the said GEORGE PALM, have hereunto set my hand.

GEORGE PALM.
